(57) CLAIM

The ornamental design for a cowboy dressage challenge court, as shown and described.

DESCRIPTION

FIG. 1 is a top perspective view of a cowboy dressage challenge court;

FIG. 2 is a front elevation view thereof, the rear elevation view being a mirror image thereof;

FIG. 3 is a left side elevation view thereof;

FIG. 4 is a right side elevation view thereof; and,

FIG. 5 is a top plan view thereof.

The broken line shown in FIGS. 1 and 2 define the bounds of the claimed design and form no part thereof.
